United States Patent Office

Des. 196,038
Patented Aug. 20, 1963

196,038

BUILDING

Robert F. Rodriguez, St. Louis, Mo., assignor to Smaks International, Inc., Prairie Village, Kans., a corporation of Kansas

Filed Dec. 26, 1961, Ser. No. 68,046

Term of patent 3½ years

(Cl. D13—1)

FIG. 1 is a front elevational view of a building, showing my new design;

FIG. 2 is an elevational view of one end thereof;

FIG. 3 is a rear elevational view of the building; and
FIG. 4 is an elevational view of the end thereof opposite to the end shown in FIG. 2; and

FIG. 5 is a top plan view thereof.

I claim:

The ornamental design for a building, as shown.
